LOG-BARKING DRUM AND TOOTHED ELEMENT THEREFOR

Caney A. Thompson, Mobile, Ala., assignor to International Paper Company, New York, N. Y., a corporation of New York

Application March 30, 1953, Serial No. 345,350

3 Claims. (Cl. 144—208)

This invention relates to new and useful improvements in apparatus for removing the bark from log billets and particularly seeks to provide a drum type of log barker which includes a series of internally positioned, toothed elements to increase the efficiency of such barkers, particularly when used on hardwood species.

The normal drum barker consists of a relatively large diameter, long, open-ended cylinder fabricated from a plurality of longitudinal stringers held together by a plurality of supporting annuli. Slots are provided between the longitudinal stringers through which the removed bark may drop. The longitudinal stringers generally present a corrugated surface on the interior of the drum so that when the drum is rotated with a charge of logs placed therein the billets will not only tumble against themselves but will abrade against the corrugations of the stringers to effect substantially complete removal of the bark. While debarkers of the foregoing description have been found generally suitable for the removal of bark from softwood species they are not particularly satisfactory for the removal of bark from hardwood species for the reason that in hardwood species the bond between the bark and the underlying wood is much tighter than the corresponding bond on softwoods, and the simple tumbling type of barking action mentioned above is inadequate to completely remove the bark.

Through the use of this invention drum type barkers are modified so that their barking efficiencies for softwood species are increased and so that hardwood species can be completely debarked. To this end the present invention provides a plurality of spaced sets of toothed elements along the full length of the interior of the drum with the spacing between adjacent sets of elements generally being substantially less than the lengths of the pulpwood billets to be debarked in order that the billets during the tumbling action induced by rotation of the drum will be certain to hit at least one of the toothed elements at each drop.

An object of this invention, therefore, is to provide a novel barking drum, particularly adaptable for the debarking of hardwood species, which includes a plurality of sets of spaced toothed elements extending along the entire interior of the drum.

A further object of this invention is to provide a barking drum of the character stated in which the toothed elements may comprise a series of serratedly-arranged plates rigidly affixed along the entire interior of the drum.

A further object of this invention is to provide a barking drum of the character stated in which for the barking of hardwood species the tooth shape consists of a high point positioned in the direction of rotation and a sloping rear surface extending downwardly away from the direction of rotation so that penetration of the high point of each tooth into the pulpwood billet will not be substantially greater than the average bark thickness on hardwood species.

A further object of this invention is to provide a bark-

ing drum of the character stated in which the tumbling action of the logs resulting from rotation of the drum is better effected by the use of a plurality of successively offset lifting plates rigidly secured within the drum.

With these and other objects in view, the nature of which will be more apparent, the invention will be more fully understood by reference to the drawings, the accompanying detailed description and the appended claims.

10 In the drawings,

Fig. 1 is a longitudinal fragmentary section of a barking drum constructed in accordance with this invention; Fig. 2 is a vertical transverse section taken along line

15 2—2 of Fig. 1; Fig. 3 is an enlarged fragmentary detail, partly in section, of one of the toothed elements shown in Fig. 2;

Fig. 4 is a vertical transverse section taken along line 4—4 of Fig. 3;

Fig. 5 is a fragmentary perspective of one of the longitudinal stringers forming the shell of the drum;

Fig. 6 is a detailed perspective of one of the basing plates used to rigidly support the contained elements;

Fig. 7 is a fragmentary development of the drum showing a modification of the positioning of the toothed elements therein;

Fig. 8 is a fragmentary transverse section similar to Fig. 2 but shows a variation in the shape of the teeth;

Fig. 9 is an enlarged fragmentary detail plan view of one of the toothed elements shown in Fig. 7;

30 Fig. 10 is a vertical transverse section taken along line 10—10 of Fig. 9;

Fig. 11 is an enlarged fragmentary elevation taken within the zone 11—11 of Fig. 9;

Fig. 12 is a vertical transverse section taken along line 35 12—12 of Fig. 11;

Fig. 13 is a fragmentary development of the drum and shows a further modification of the positioning of the toothed elements therein;

Fig. 14 is a partly schematic left end elevation of the 40 barking drum modified by the addition of a plurality of successively offset bar-supported lifting plates; and

Fig. 15 is a somewhat schematic side elevation of the barking drum illustrated in Fig. 14 but with a substantial portion of the shell broken away in order to more 45 clearly illustrate the relative positions of the bar-supported lifting plates.

Referring to the drawings in detail, this invention as illustrated is embodied in a two-section cylindrical barking drum generally indicated at 5, each section of which comprises a plurality of longitudinal stringers 6 arranged in spaced cylindriform relationship and rigidly affixed as by welding to a plurality of externally positioned rings or annuli 7. The drum is adapted to be rotated through a ring gear 8 rigidly affixed to the exterior thereof and a driving gear 9 operatively connected to any suitable source of power. The barking drum is rotatably supported upon a plurality of pairs of grooved rollers 10, 50 55 which receive certain of the rings 7.

The interior of the barking drum is provided with a 60 plurality of annular toothed elements generally indicated at 11 and arranged in spaced parallel relation along substantially the full length of the drum. Each of the annular elements 11 is formed from a plurality of arcuate segments 12 rigidly affixed to each other and to the adjacent longitudinal stringers 6. Lateral deflection of the annular elements 11 is prevented by providing each of the arcuate segments 12 thereof with one or more gusset plates 13 rigidly affixed to the segments 12 and to the adjacent longitudinal stringers 6. The inner edges of the segments 12 are provided with a continuous series of 65 generally sharp, pointed triangularly-shaped teeth 14.

By the provision of the internally toothed annular ele-

ments 11 operation of the drum for the debarking of the pulpwood billets will be effected in the normal manner by simple rotation of the drum through the driving connections 8 and 9. However, as the billets are fed into the receiving end of the drum and a small pile thereof accumulates and gets tumbled over and over as the result of the rotation of the drum the uppermost billets of the pile progressively will fall down and contact the toothed surfaces of the annular elements 11 and the teeth 14 thereof will penetrate the bark on the billet to facilitate its removal as the tumbling action continues. It may be noted at this point that most barking drums used today are designed to operate upon pulpwood billets having a length of 4 feet. Accordingly, the spacing between adjacent annular elements 11 should be slightly less than the length of the pulpwood billets in order to assure successful and multiple contacts of each billet with the teeth 14 as the billet progresses through the drum.

In Figs. 7 through 12 of the drawings there is illustrated a barking drum containing a modified type of internally disposed toothed structure. The purpose of this is the same as that heretofore described in connection with the annular elements 11, but by use of this modified form it is possible to construct the barking drum as a shell formed from plate iron or steel rather than fabricating the drum from a plurality of longitudinal stringers held in cylindriform arrangement by the externally positioned mounting rings 7.

Fig. 7 of the drawings discloses a development of the interior surface of a portion of a barking drum containing the modified toothed elements with the drum axis corresponding to that of Fig. 1. In this form the plating of the shell of the drum is indicated at 15, and it will be seen that the internally positioned toothed elements comprise a plurality of rows 16, each of which is formed from a plurality of toothed elements 17 arranged in a serrated or zigzag manner. The lower apex between each pair of elements 17 is filled by a reinforcing plate assembly 18, and immediately thereabove as viewed in Fig. 7 and 9 the shell 15 is slotted as at 19 to provide an aperture through which the free bark may drop during the course of debarking operations. In this form of barking drum the teeth of the element 17 may be shaped the same as the teeth 14 of the arcuate segments 12 or preferably they should be contoured as indicated in the enlarged fragmentary view shown in Fig. 11 which may be described as somewhat chisel-shaped in that the leading edge 20 terminates in a sharp corner 21 and the tooth then exhibits a downwardly and rearwardly slanted flat portion 22 and a trailing edge 23. This shape of tooth is particularly advantageous in connection with the removal of bark from hardwood species in which the actual thickness of bark is substantially less than that normally appearing on softwood species. With this form of tooth whenever a pulpwood billet falls from the tumbling pile onto the toothed elements 17 the sharp corner 21 will penetrate the bark, but the flat, rearwardly slanting portion 22 of the tooth will prevent penetration greater than the thickness of the bark. In this manner the bark can properly be removed without any unnecessary splintering or brooming of the underlying wood.

Again, in this form of toothed elements lateral bending thereof may be prevented through the use of gusset plates 24 rigidly affixed to the elements 17 and to the adjacent shell 15.

In Fig. 13 there is illustrated a further modification of barking drum which may be fabricated either in the general form illustrated in Fig. 1 or the modified form as indicated in the development of Fig. 7. The present modification as illustrated in the fragmentary development of a barking drum shown in Fig. 13 provides for a continual helix of toothed elements in the drum. In this form the drum shell is indicated at 25 and the toothed

elements at 26 and the axis of the drum corresponds to that of Fig. 1. In this case also the pitch of the helix should be slightly less than the length of the pulpwood billets to be operated upon in order to assure multiple contacts of each billet with the toothed elements 26 during its passage through the drum.

In connection with the debarking of certain hardwood species where the bond between the bark and the underlying wood is particularly tight, it may be found necessary to augment even the supplementary barking action as effected by the above described toothed elements by the addition of lifting plates or paddles to accentuate the tumbling action of the pulpwood billets as the drum is rotated. To this end each section of the barking drum 15 may be provided with a plurality of internally fastened, diametrically extending cross bars 27 spaced along the length of the drum as indicated in Fig. 15 with successive cross bars being angularly offset with respect to the adjacent cross bar by an angle preferably of 45°. Each end of each cross bar is provided with a lifting or tumbling plate 28 fastened to the inner surface of the cylinder and to the lead face of the cross bar, i. e., that face in the direction of rotation.

It is, of course, to be understood that various details of arrangements and proportions of parts may be modified within the scope of the appended claims.

I claim:

1. In a barking drum wherein is provided an open-ended cylinder, means for rotatably supporting said cylinder; the combination of a multiplicity of longitudinally extending rows of arcuate toothed elements rigidly affixed to the interior of said cylinder in positions to be contacted by individual wood billets as the result of tumbling action induced by rotation of said drum, the toothed elements of each of said rows comprising a multiplicity of individual toothed elements arranged zigzaggedly, each tooth of said toothed elements when viewed from one side thereof including a leading edge extending substantially radially with respect to the axis of rotation of the drum and terminating in a sharp inner corner, a trailing edge spaced from said leading edge, and a flat surface extending between said sharp inner corner and said trailing edge, said flat surface sloping outwardly towards the periphery of said drum.
2. A barking drum in accordance with claim 1 in which the cylinder is provided with a plurality of diametrically positioned cross bars rigidly affixed therein along the length thereof, each successive cross bar being angularly offset with respect to the adjacent cross bar and being provided at each end with a lifting plate rigidly secured thereto and to the adjacent face of the associated cylinder.
3. A toothed element for a barking drum comprising an arcuate plate provided along its inner concave edge with a multiplicity of bark-engaging teeth, each of which when viewed from one side of said plate includes a leading edge extending substantially radially with respect to the axis of curvature of said arcuate plate and terminates in a sharp inner corner, a trailing edge spaced from said leading edge, and a flat inner surface extending between said sharp inner corner and said trailing edge, said flat inner surface sloping chordally from said sharp inner corner towards the proximate portion of the periphery of curvature of said arcuate plate.
